Attorney

UNITED STATES PATENT OFFICE.

JOHN CLAYTON, OF CUYAHOGA FALLS, OHIO.

TROLLEY.

SPECIFICATION forming part of Letters Patent No. 600,633, dated March 15, 1898.

Application filed November 4, 1896. Serial No. 611,013. (No model.)

To all whom it may concern:

Be it known that I, JOHN CLAYTON, a citizen of the United States, residing at Cuyahoga Falls, in the county of Summit and State 5 of Ohio, have invented certain new and useful Improvements in Trolleys; and I do hereby declare the following to be a full, clear, and exact description of the invention, such as will enable others skilled in the art to 10 which it appertains to make and use the same.

My invention relates to electric trolley-wheels.

Heretofore considerable difficulty has been experienced in using trolley-wheels, owing to 15 the fact that frequent lubrication was necessary in order that the wheel might run smoothly. Another difficulty has also been experienced, as the trolley-wire is liable to "jump" the trolley-wheel when the car is 20 moving rapidly or going around a curve.

The object of my invention is to provide a novel form of trolley-wheel which will be self-lubricating for a comparatively long period of time, thereby doing away with the expenditure 25 of time and labor.

A further object is to provide improved means adapted to prevent the trolley-wire from jumping the wheel.

Having these objects in view, the invention 30 consists in the combination, with a trolley-wheel, of a hollow bearing therefor, which is adapted to hold a lubricant and is provided with outlets, so that the lubricant will be delivered to the bearing-surface of the wheel as 35 the latter revolves.

The invention further consists in certain improved guards adapted to prevent the trolley-wire from jumping the wheel; and it further consists of certain other improved features and novel combination of parts appearing more fully hereinafter.

In the accompanying drawings, Figure 1 is a side elevation, Fig. 2 an end view, Fig. 3, a cross-sectional view, and Fig. 4 a detail 45 view, of the hollow bearing for the wheel, the latter being removed, said view disclosing one pair of lubricating grooves.

The numerals 1 and 2 designate duplicate sections or halves of the head, and these clasp 50 around and are secured to the trolley-pole 3. The sections of this head are provided with hollow bearing-sections 4 and 5, said sections

being formed integral with the respective sections of the head. Each bearing-section is provided with opposite lubricating-grooves 55 6 and 7, which slant downwardly. These grooves are deepest at the inner edge of the section, where a semicircular hole 8 is formed, which leads into the interior of the section. It will thus be observed that when the bearing-sections abut on each other there are provided two circular holes 9 and 10, through which the lubricant contained within the bearing-sections can find its way out into the grooves. 65

The numeral 11 designates the trolley-wheel, which is snugly yet easily received on the bearing-sections. At 12 is shown a bolt which passes through the bearing-sections from side to side of the head and is provided 70 with a nut 13 on its ends. The lubricant employed should be solid or substantially so, and it is introduced in the bearing-sections, the latter projected into the trolley-wheel, and then the parts are clamped together by the 75 bolt and nut. As the wheel revolves the lubricant passes out through one of the circular openings and into the inclined grooves that lead therefrom, so that said lubricant is distributed over the entire width of the bearing-surface of the trolley-wheel. Of course it is 80 obvious that as many of the openings and lubricating-grooves could be employed as found desirable; but I find that two sets are generally sufficient, and hence have only 85 spoken of that number. The capacity of the bearing-sections being quite great, the wheel will be self-lubricating for a number of days.

I will now proceed to the description of the means adapted to retain the trolley-wire on 90 the wheel. Connected to each section of the head there is a curved or arc-shaped guard 14, and this guard lies immediately outside the faces of the wheel and projects up above the periphery thereof. It can be made of any 95 desired width and is well adapted to guide the trolley back into the wheel should it jump from the latter.

Having thus described my invention, what I claim, and desire to secure by Letters Patent, is—

1. The combination with head-sections adapted for connection to the trolley-pole, of hollow bearing-sections connected to said

head-sections and adapted to contain the lubricant and extending inwardly and having their inner edges meeting, each bearing-section being provided with a lubricating-opening, and a trolley-wheel mounted to turn on said bearing-sections.

2. The combination with head-sections adapted for connection to the trolley-pole, of hollow bearing-sections connected thereto and 10 having their inner edges meeting, said sections being adapted to contain the lubricant each section being provided with an inclined laterally-extending lubricating groove in communication with the interior of the bearing-sections, and a trolley-wheel mounted on said bearing-sections.

3. The combination with head-sections adapted for connection to the trolley-pole, of 15

hollow bearing-sections connected thereto and projecting inwardly and meeting, said sections being adapted to contain the lubricant, each bearing-section being provided with an inclined lubricating-groove which leads from the edge of the section laterally, said grooves being disposed in sets which meet at the edges 20 of the bearing-sections, a trolley-wheel mounted on said bearing-sections, and means for holding the head-sections together.

In testimony whereof I have signed this specification in the presence of two subscribers. 25 30

JOHN CLAYTON.
